10 Claims.

(Cl. 12—17)

This invention relates to a device for finishing the soles of shoes, and has for its object to carry out the levelling process forming the last step in finishing in a novel manner simultaneously with the closing of the channel and the setting of the sole edge in a single operation by a machine combining all the tools required for the various operations.

In the mechanical production of shoes the problem of levelling the soles has not been solved as yet in a satisfactory way, and the known methods and devices for this purpose are open to serious objections which the trade has been trying to overcome for a long time.

15 All known levelling devices require the use of molds which must be specially constructed for each type of last in at least two sizes.

The machine according to the invention eliminates all these drawbacks and makes it possible 20 for the first time to carry out levelling without using metal or wooden lasts and metal molds.

Furthermore, the invention permits levelling simultaneously with channel closing and edge laying in one operation by combining in one and 25 the same machine the levelling tools with the tools for closing the channels and laying the sole edge in such manner that they operate automatically in positive dependence upon one another.

The simultaneous carrying out of the auxiliary operations of channel closing and edge laying 30 by means of a roller closing the lip and feeding the work and of a hammerlike laying tool is known. It has further been proposed to provide devices of this class with a work carrier for supporting the work against the vertical pressure 35 exerted by the channel closing roller at the seam and, simultaneously, for taking up the impacts due to the beatings of the setting hammer occurring transversely thereto, and also with a lip layer arranged in front of the closing roller.

40 These devices serve, however, solely for performing the auxiliary operations of channel closing and edge laying, which, according to the invention, are combined with the main levelling operation of the new device merely in a supplementary manner, so that the new combination represents a novel universal sole finishing machine.

In contradistinction to all known levelling devices the new machine makes allowance in a perfectly simple and safe manner for different working of the sole in the shank and outer bottom portion, as required in levelling, and can further be adapted to any shoe sizes without the least trouble and without the use of lasts or molds and even permits special handling of particularly delicate products.

Besides those mentioned, the invention affords other advantages which are pointed out in the 60 following specification with reference to the ac-

companying drawings, in which Figure 1 is a side view of the device, partly in section; Fig. 2, a top view of the machine head; Fig. 3, a vertical section on an enlarged scale showing the working tools arranged in the machine head; Fig. 4, a detail view on an enlarged scale of the work carrier; and Fig. 5, a detail view of an operating lever.

Referring to the drawings, the machine comprises a stand 1 which supports the machine head 10 on a bearing 15, and a horn-shaped work carrier 18 provided with a work receiving plate 9 which is preferably rotatable on ball bearings.

The member 18 can be lowered in usual manner, for instance by means of a foot lever, not 15 shown, against the pressure of a spring tending to force it up.

The machine head 24 rests on a slide plate 72 which is arranged on the standard 1 and on which the machine head 24 by means of the hand wheel 20 21 and the spindle guide 76 can be moved in the direction of the shoe or away from the latter by means of the block 75 engaging the head and running on the spindle.

The machine head 24 supports at its rear end 25 the driving motor 2 which drives the pulley 4 by the belt 3. The pulley 4 acts by means of a worm, etc., not shown, on a worm wheel arranged on the main driving shaft, not shown.

The driving shaft carries at its front end a 30 roller which is subdivided several times to form a plurality of different discs of which four are shown. Only one of the middle discs 8^a is driven, and the other discs 8^b, 8^c and 8^d are rotatably disposed on the shaft by means of the ball 35 bearings 68.

This roller as shown is of cylindrical form, though it may also be of conical, concave or convex shape. The driven disc or roll 8^a is preferably fluted and serves for feeding the work, 40 of which only the shoe sole is shown in Fig. 3 through the gap between the disc and the work carrier over the channel lip. The loosely disposed discs have preferably a smooth surface.

Below the roller 8 and parallel to the surface 45 thereof a setting hammer or beater 11 is positioned which is operated by the cam shaft 13. The cam shaft is driven by a belt 14 which passes over the pulley 35 and the pulley 5 arranged on the shaft 4a so as to be driven by the motor 2.

The cam shaft 13 actuates the hammer 11 only when the work exerts pressure upon the point thereof.

In a novel manner a welt edge or seam hammer 63 is provided below the setting hammer 55 11, as indicated in Fig. 3. The hammer 63 operates in such manner that while the setting hammer 11 works in the direction of the surface line of the pressure roller 8 the hammer 63 applies the same number of blows upon the seam from 60

below in vertical direction. This operation is carried out also through the medium of the cam shaft 13, since during the advance of the hammer 63 in a manner to be described below a cam 5 stop 67^c at the rear end thereof moves within working range of the cams which thus apply the same number of blows received by the laying hammer 11 to the rear end of the hammer 64. As the hammer 63, 64 is inclined on the 10 member 18, the downwardly acting blows of the cam are converted into blows applied to the seam from below in vertical direction by the exchangeable pointed end 63 of the hammer. The spring 66 or the support controlled thereby which is secured to the base plate of the displaceable head 24 tends to lift the rear end of the hammer 63, 64 and to return it to the cam path. The spring 63 serves for cushioning the hammer 63, 64 to 15 compensate for irregularities in the width of the sole edge. The working point of the hammer 63, 64 shown in Fig. 3, possesses two angularly disposed surfaces one of which is arranged horizontally in working position and the other one at an angle thereto. In this manner, accurate 20 meeting of the seam and working groove is insured and the hammer is further prevented from touching any outsole stitching or edging. To permit working of soles of any size and thickness the hammer 63, 64 can be adjusted in vertical 25 direction.

A particular feature of the invention is that the hammer 63, 64 during working of the shank is automatically stopped or started when the edge of the sole is to be treated.

30 This purpose as well as another one to be explained below is served by the movable arrangement of the entire machine head 24 which is disposed between guide members 70 firmly connected with the machine stand 1 and united by a covering plate 69, as shown in Fig. 1. The guide 35 members 70 possess guide curves, indicated by dotted lines, along which the slide plate 72 carrying the machine head and provided with corresponding guide projections can be swung. This motion is carried out about a horizontal axis α 40 which passes through the center of the lower surface line of the driven pressure roller disc 8^a. During the swinging motion this point retains its position, that is, the tilting of the machine 45 head about the axis passing through it does not produce an increase or reduction of the pressure 50 acting upon the work located between the horn 10 and the roller 8. Only the outer loosely disposed rolls 8^b, 8^c, 8^d are moved during the 55 passage from oblique into horizontal position, which occurs simultaneously with the transition from shank working to that of the flat sole portion, into a position adapted to the plane of the sole against which they continue to abut.

60 The machine head 24 is tilted by means of a bar 82 which is actuated by a knee support 85, shown in detail in Fig. 5, and which is fitted at its end with a rack gear which acts on a gear wheel 80. The gear wheel 80 is internally threaded and engages the threads of the rod 79 so as to move the link 77 which is pivotally connected to the rod 79 as indicated at 78. The other end of the link 77 is connected to the slide plate 72 65 at 74 so that the machine head may be tilted by actuation of the member 85. The gear wheel 80 is rotatably mounted and retained against axial movement by the bracket 81 which is secured to the frame 1. Two set screws 92 permit instantaneous adjustment of the lower and up- 70 75

per limit of this lifting motion relative to one another.

To reduce the expenditure of energy required for lifting the machine head to a minimum a counterweight 88 is provided which is suspended from an eye 90 of a rope 89 which passes over pulleys 86, 87 and secured to the link 77 at 90^a.

Through a special coupling of the hammer 63, 64 with the fixed guides 70 of the stand 1 the hammer will be inoperative when the machine head 24 is inclined and thus in a position for working the shank. The hammer is articulated at 67^a to the control lever 67 secured at 67^b to the member 70, and the arrangement is such that at horizontal position of the machine head 24 the point 63 of the hammer 63, 64 is located exactly vertically under the point of the hammer 11, though this position can of course be adapted to other angular positions of the machine head by displacement of the pin 67^c.

When the machine head 24 is tilted out of the inclined position shown in Fig. 1 into horizontal position, the previously withdrawn hammer is moved forward by the link 67 and thus passes with its rear cam 67^c within range of the cam shaft 13, whereby the vertical swinging motion of the hammer is started and thus the corresponding action on the edge of the work.

Another essential feature for attaining the full effect of the new device is the special construction or operation of the horn-like work carrier. The work carrier is preferably heated as in other types of shoe machinery, such as sole sewing machines. Current is supplied for this purpose by the conductors 50+ and 50- which are in sliding contact with the separately insulated members 46+ and 46- of the sleeve 98 through the inside of which a conductor connecting with the member 46+ is passed to which the heating device of the horn 10 is connected while the return line is represented by the sleeve 98 itself.

A shaking motion is imparted to the work carrier, particularly if shoes are to be worked which like orthopedic ones have an insole requiring special treatment, such as underlaid rubber fabrics, etc. This motion prevents the insole from getting out of proper position, as the support, as it were, merely jumps over it.

For this purpose the horn guiding bearing 97 is provided, as shown in Fig. 4, which is arranged in the horn bearing 15 and can move only up and down. In the bearing 97 moves the bushing 98 which rotatably supports the horn 10. The springs 96 press the bearing 97, the bushing 98 and the horn support 10^a against the work. The extension of the horn which is non-displaceable in the bushing 98 and secured by the nut 106 is connected with the eccentric 102 by the member 100 and the connecting rod 101. The eccentric 102 is driven by a shaft 102a and a grooved pulley 103 or the like from a suitable power source. The shaft 102a is provided with a collar 105 for preventing axial movement thereof. The rod 104 is provided for establishing a connection to the foot lever adapted for raising and lowering the horn. The extension 97^a of the guiding bearing 97 supports the eccentric shaft. The bearing 97 is displaceable relative to the bushing 98 to a somewhat greater extent than the stroke of the eccentric. When the horn 10 is under pressure against the shoe and the eccentric 102 moves, the counter-pressure of the springs 96 will be quickly eliminated, so that the horn is relieved from spring pressure and the resulting increasing and decreasing pressure imparts a jolting mo-

tion to it. The cam shaft is preferably driven at a speed of approximately 3,000 revolutions per minute.

The machine functions as follows:

- 5 Assuming that a shoe having a half-round shank and plane bottom with broad double sole edge is arranged in the apparatus the machine is first adjusted once and for all to a certain tilted position which in the example assumed involves an inclination of eight to zero degrees relative to the horizontal.

When work is to start on the shank, the machine at the beginning of operation is in the position shown in Fig. 1, or the cylindrical feed roller is positioned at an angle of 8° relative to the horizontal while the hammer 63 is withdrawn by the link 67 and thus outside the sphere of action of the cam shaft 13. The shoe is placed on the horn carrier, previously pressed down by foot lever, and elastically pressed by it against the feed roll 8a. The heated support irons the seam under pressure.

Before the working gap is reached, the lip layer 26 driven by the pulley 30 and the belt 33, Fig. 2, brings the channel lip within working range of the pressure roller which presses the lip and levels it while the hammer 11 beats the channel edge. When the shank portion of the edge has passed through the gap, the operator 30 tilts the machine head and thereby the feed roller into horizontal position by actuating the bar 82. At the same time, through the medium of the link 67, the rearward cam projection of the hammer 63 is brought within range of the cam shaft and starts beating in vertical direction. The shoe is guided in horizontal position through the working gap, and the loose rolls 8, 8a serve as abutments for it. When working has progressed to the shank again, the machine head is moved to an inclined position, etc.

The distance of the hammers 11 and 63 from the sole and edge can be rapidly adjusted by means of the spindle 39. The rapid adjusting means for limiting the tilting motion, which need be fixed only once for each line of manufacture, includes the screws 92 for limiting the stroke of the bar 82.

The arrangement of loose rolls in addition to the driven roller portion, whereby a perfectly plane bottom is produced, prevents also any braking effect of the roller, as the rolls are independent from one another with respect to circumferential speed.

By adjusting the tilting angle any desired adaptation to shank and sole working can be effected, and a manufacturer is in a position to produce at will any type of bottom, from straight to curved, and also a corresponding shank.

It is to be further noted that the tilting of the machine head permits automatic removal of the two hammers from the work according to the requirements of a wider sole distance from ball to ball.

The invention is not limited to the embodiment shown and described, but may be varied in many respects without deviating from its fundamental idea. If the machine is to be used only for levelling, both hammers and the lip layer could be dispensed with but the employment of a swingable levelling roller would still represent an independent invention.

Furthermore, the relative position of the two hammers may be so altered that in tilted position the hammer 63, 64 projects somewhat be-

yond the hammer 11 or the hammer 63, 64 may be permanently disengaged if required. The shaking motion of the horn can also be disconnected.

We claim:

1. Apparatus for finishing the soles of shoes comprising in combination, a frame, a spring-supported work carrier, a machine head tiltably mounted on the frame, a roller rotatably mounted on the head so as to evolve immediately above the sole of a shoe supported on the work carrier, means for tilting the machine head relative to the machine frame, and means for guiding the machine head so that during the tilting thereof the machine head turns about an axis defined by a tangent of the roller.

2. Apparatus according to claim 1 wherein the machine head is arranged to be tilted so as to swing about an axis which extends tangentially through the center of the lower surface of the roller.

3. Apparatus according to claim 1 wherein the roller is positioned at one end of the machine head, and the guide means comprises arcuate shaped members for guiding the tilting movement of the head.

4. Apparatus according to claim 1 wherein the means for tilting the machine head comprises a link member pivotally connected to the head, and means carried by the frame for longitudinally moving said link.

5. Apparatus according to claim 1 wherein a driving motor is disposed on the tiltable head.

6. Apparatus for finishing the soles of shoes comprising in combination, a frame, a spring-supported work carrier, a machine head tiltably mounted on the frame, a driven roller carried by the head so as to rotate adjacent the sole of a shoe supported on the work carrier, a hammer-like laying tool carried by the head and mounted to move in the direction of the lower surface line of the roller, a second hammer-like tool movably mounted on the head to strike the welt edge of the shoe, and a cam shaft for actuating both of said hammer-like tools.

7. Apparatus according to claim 6 wherein means is provided for guiding the tilting movement of the head, and the second hammer-like tool is coupled to the guide means in such a manner that the second tool is disengaged from the actuating means when the head is tilted with respect to the horizontal.

8. In apparatus for finishing the soles of shoes, a horn-shaped spring supported work carrier having a work supporting surface, a roller against which the work carrier presses the shoe, tiltable means supporting said roller which during working of the shoe sole is arranged in a level position and during working of the shoe shank is tilted in accordance with the inclination of the surface of the shank.

9. Apparatus according to claim 8 wherein the roller comprises a plurality of individual discs mounted on a common shaft with one disc coupled to the shaft, and the other discs rotatably arranged on the shaft.

10. Apparatus according to claim 8 wherein a hammer-like laying tool acting in a lateral direction upon the work is associated with the roller, a hammer-tool simultaneously acting in an upward direction on the shoe sole edge, and a lip layer disposed in front of the working gap.
